WRITING CASE

Harry J. Waechter, Mount Healthy, Ohio, assignor to Paul Benninghofen and Fritz G. Diesbach, trustees, both of Hamilton, Ohio

Application October 16, 1936, Serial No. 106,009

2 Claims. (Cl. 282—12)

This invention relates to improvements in autographic manifolding or writing cases and preferably to a type which can, as a book, be carried about by the user. The improvement employs continuous stationery or webs of paper, flat packaged by zig-zag folding, for manifold inscription in plural ply number, which is unfolded from the package as it is used and extended over a writing platen to expose and sustain a section for writing thereon.

The web or webs are sub-divided into sheet sections by fold lines or transverse tear lines, or provided with longitudinally spaced indicia, as perforations. The perforations are adapted to function in cooperation with pins or other media in arresting web withdrawal for sequential or sectional extraction, positioning and locating a successive section over the writing platen, and to prevent longitudinal displacement thereof. The utility of such class of stationery is well known commercially so that all of its benefits and advantages need not be enumerated herein.

An object of the invention is to provide a flat, diminutive writing case for portable service, compactly housing continuous web stationery flat packaged, unfolded as used by drawing the same over a writing platen, as the top of the case, to sustain and expose a section thereof for writing thereon, its withdrawal from the case being automatically controlled for sequential, sectional or regulated length extraction by pins or other media engageable through apertures in the web. The control means is operative to release the web by a thrust imparted by the hand of the user in obtaining a fingerhold on the leading end of the web and in the withdrawal or extraction thereof.

Another object of the invention is to provide a storage receptacle immediately beneath the writing platen, open at an end or side of the case for slipping in and depositing extracted sections when severed from the web.

Another object of the invention is the utilization of carbon coated sheets interleaved between the web sections upon the writing table for manifolding the sheet or sheets, readily installed and held against translation with the web.

Other objects and further advantages will be more fully set forth in a description of the accompanying drawings, in which:

Figure 1 is a top plan view of the improved writing case.

Figure 2 is a perspective view of the case with the writing platen in an upright position.

Figure 3 is a detail perspective view of the rear end of a section of the case, illustrating the

method of anchoring the rear end of the carbon sheets interleaved between the work plies upon the writing platen.

Figure 4 is an enlarged section on line 4—4, Figure 1.

Figure 5 is an enlarged section on line 5—5, Figure 1.

Figure 6 is a detail perspective view of a section of the forward end of the writing case, showing the parts in their position in the act of an operator extracting the leading end of the web or webs with which the case is loaded.

Figure 7 is a section on line 7—7, Figure 1, with a modified form of writing platen as of double-wall structure to provide a storage receptacle.

Figure 8 is a section on line 8—8, Figure 1, with the modified form of writing platen as illustrated in Figure 7.

Referring to the drawings, 1 indicates a case or container formed of sheet material having an open upper side, and of an outline and shallow depth dimension to compactly store a definite sheet size package of stationery in continuous form, zig-zag folded, either single or plural ply, the plural ply serving for making manifold copies. The case in outline dimension approximates that of a given sheet size and is of comparatively shallow depth so that it can be conveniently carried about and as accommodative as a writing pad.

The webs of paper 2, for the number employed, are preferably sub-divided into sheet sections by transverse tear lines 3. Following the general practice for stationery employed in autographic registers, the tear lines are located at the lines of fold and each section, in the margin of a head end thereof, is provided with a pair of apertures 4—4 which are used for withdrawal control, registration of the form matter on the sheet section disposed over the writing table in the plural ply, and to appropriately locate the successive sections upon the writing table.

A writing platen 5, at its forward end, is hingedly connected to the forward ends of the opposite side walls 6—6 of the case for swinging the platen upwardly from a horizontal position, as a cover for the top of the case, into an open position to permit a package to be deposited within the case.

The platen is formed of sheet material, flanged at its opposite longitudinal edges for reinforcement and hingedly connecting the same to the side walls of the case. The flanges 7—7, projecting at an angle from the lower side of the

platen, thus extend into the inside of the case when the platen is in its closed or normal position.

The edges of the flanges respectively engage 5 stop lugs 8-8 formed by indenting the side walls of the case to limit the inward swing of the platen and station the platen within the case with its upper surface slightly recessed below the top edge of the side walls, so that the upper 10 portion of the side walls serves to longitudinally guide and confine the portion of the webs upon the writing table against lateral displacement.

The rear end of the writing platen is scrolled to provide a curved end, over which the webs can 15 freely pass as they are withdrawn over the platen from the supply compartment therebeneath. The front wall 9 of the case is inclined inwardly to have the front end of the writing platen overlap and project therebeyond within the dimensions of the case, and provides a finger clearance 20 to enable the leading end of the webs to be manually grasped for withdrawal. The platen, centrally at its forward end, has a notch 10 for access into the leading end of the webs.

25 A cross bar 11 extends across the forward end of the writing table and has its opposite ends bent at an angle or flanged for hingedly connecting the same to the side walls of the case, swinging on the fulcrum which hinges the platen to the casing. The cross bar is spaced slightly from the top of the platen for threading the leading ends of the webs therebetween and provides a passageway through which the webs are withdrawn. The cross bar carries a pair of pins 12-12 fixed to 30 and laterally projecting respectively from the opposite ends of a leaf spring 13, fixed to the top side of the cross bar at a slightly elevated position therefrom.

Each of the pins is adapted to engage through 40 an aperture in the cross bar and through an aperture in the webs when brought in registration therewith to arrest web withdrawal. The pins are expressed from the aperture to permit web withdrawal by a slide plate 14, slidably mounted 45 upon the upper side of the cross bar 11, intermediate the cross bar and pin carrying leaf spring 13.

The slide 14 has a central elongated notch 15 traversed by a stationery guide 16, elevated from 50 the top of the cross bar 11 upon which the pin carrying leaf spring 13 is mounted and fixed. A pair of cam or wedge formations 17-17 are struck up from the body of the plate to provide inclines 55 engaging beneath the leaf spring 13 at relative opposite sides of its mounting, upon sliding the plate 14 rearwardly, elevating the pins to extract the same from the web controlling apertures 4-4.

The forward end of the slide plate is of a formation 60 providing a thumb hold 18 and a tear edge 19 for continuing the forward tear edge of the cross bar 11, which is interrupted by a notch 20 cut into the cross bar 11 which the slide plate gaps. The notch 20, at the forward edge of the cross bar, provides a clearance to expose a portion 65 of the leading edge of the webs when the slide is thrust rearwardly by the thumb of one hand of the operator, uncovering the notch, allowing the thumb to be brought on the upper side of the leading edge of the webs and the forefinger on the lower side thereof through the notch 10 in 70 the front end of the writing platen.

The slide is automatically retracted by a spring 75 21 as the operator releases the same while withdrawing the web, which again frees the pins 12-12, adapting the same to yieldingly bear upon

the webs ready to snap through a successive set of apertures when brought into registry therewith for stopping web withdrawal. The spring 21 is of bar type, centrally fixed upon the guide 16, thereby providing oppositely extended limbs having 5 their free ends connecting with the slide plate, preferably by engagement, each through an eye 22 formed by outwardly expressing a loop from the body of the slide plate.

The rear margin of the slide plate is angled to 10 form a stop flange 23 for engagement with the rear edge of the cross bar 11 for limiting the normalizing movement of the slide plate. The slide plate, moving in a plane parallel with the webs, is moved rearwardly without effort and under the 15 act of obtaining a fingerhold upon the leading edge of the webs, thereby lifting the pins out of the web apertures. The parts automatically move to their normal positions as the fingers of the operator move away from the same in the act of 20 withdrawing the webs for a successive functioning of the pins, to arrest web advance after a measured web withdrawal interval, thereby affording a facile method of operation.

The writing platen and the cross or tear bar 25 being hinged to swing in the same direction allow both to be simultaneously moved to an open position upon raising the platen for access into the case when it is necessary to replenish the web supply, and upon closing the platen the cross bar 30 will remain in its open position to facilitate in threading the leading edge of the webs therebeneath and for adjusting the webs to bring the edges in a position for registration with the arresting pins, and restrained against movement 35 upon swinging the cross bar to its normal or closed position.

For manifolding work a plural ply of webs is employed and a carbon coated sheet 24 is interleafed between adjoining portions or sections of 40 the webs disposed over the writing table, the carbon sheet extending longitudinally with the direction of web withdrawal and having a margin of its rear end lapped over a flexible metal strip 25 to bind the same against displacement or from 45 being disturbed under the advancing pull of the webs in extracting a leading section thereof.

The margin of the carbon coated sheet is preferably lapped over the cross strip 25 in a manner in which its carbon coated side is unexposed and 50 bears against the opposite side of the strip to avoid web smudging when the webs are withdrawn.

A flexible metal guard strip 26 is disposed over 55 the rear end of the writing table and bears upon the webs to hold the same flat upon the writing table. The opposite ends of the cross strips 25 and 26 are formed with tabs for socketing into apertured ears or lugs 27 struck out of or secured 60 on the side walls of the case. The carbon sheet holding strips and the guard strip for the construction shown are displaceably mounted for facilitating in interleaving the carbon sheets between the webs and in adjusting the same upon the writing table, although it is obvious that these 65 parts may be permanently mounted upon the case or writing platen if desired.

For some uses it is desirable to store the duplicate copies of the sheet sections as they are dispensed and severed from the web, within a receptacle or compartment within the case. Therefore, as shown in Figures 7 and 8, the writing platen is formed of double panels, preferably from a single sheet of material, with the space intervening the panels providing a receptacle 70 75 28

partially open at its front end, the rear end being closed by the wall joining the panels and which is rounded to serve as a guide for freely translating the webs thereover in extending the same 5 from the storage compartment onto the upper panel, as a writing platen.

The front end of the lower panel is bent inwardly to provide a partial closure for the front end of the receptacle and with the upper panel 10 forms a slot opening through which the sheet sections can be slipped for deposit within the receptacle 28, one upon another, the deposited sections being confined within the receptacle against accidental discharge under the portable use of the 15 apparatus.

One or both sides of the receptacle are open for removal of the sheet sections when the receptacle or panel unit is swung to an open or upright position, with the side walls of the case serving as 20 closures for the open sides of the receptacle when the panel unit is closed.

Having described my invention, I claim:

1. In a device of the class described, a case for compactly housing a flat package of continuous 25 web stationery, a writing platen providing a top for the case over which a leading end of the web, unfolded from the package, is extended for writ-

ing thereon, a cross bar bridging the platen at a web delivery end of the case, a leaf spring fixed upon the cross bar to provide a pair of oppositely extended limbs, each carrying a pin for movement transversely to the platen for engaging 5 through apertures in the web to arrest web withdrawal, and a reciprocable slide on said cross bar for flexing the limbs to extract the pins from the web apertures, the slide actuated by a finger thrust in the act of the operator grasping the 10 leading end of the web for withdrawing the same, accessible from beneath said slide.

2. In a device of the class described, a case for compactly housing a flat package of continuous web stationery, a double-walled top liftably 15 mounted between the side walls of the case and providing a writing platen, over which a leading end of the web, unfolded from the package, is extended for writing thereon, said top forming a storage receptacle and having a constricted open- 20 ing at the web dispensing end of the case for depositing dispensed web sections after being severed from the web, and said top having a full, open side normally closed by a side wall of the case for discharging the stored sections upon lifting the 25 top from the case.

HARRY J. WAECHTER.
